FIG. 6

INVENTOR,
May C. Whitmore,
BY Howard J. Smith
ATTORNEY.

UNITED STATES PATENT OFFICE.

MAX C. WHITMORE, OF DAYTON, OHIO, ASSIGNOR TO JOSEPH R. KATHRENS, TRUSTEE,
OF WEST MILTON, OHIO.

FILING CABINET.

Application filed April 12, 1923. Serial No. 631,505.

To all whom it may concern:

Be it known that I, MAX C. WHITMORE, a citizen of the United States, residing at Dayton, in the county of Montgomery and 5 State of Ohio, have invented certain new and useful Improvements in Filing Cabinets, of which the following is a specification.

This invention relates to new and useful 10 improvements in filing cabinets of the type illustrated and described in my application Serial No. 600,830 filed November 14th, 1922, and has particular reference to a simple, compact and convenient cabinet of that type, 15 which may be used for home budgeting and like purposes.

One convenient form of embodiment of 20 my invention is illustrated in the accompanying drawings, of which Figure 1 is a longitudinal, sectional view taken through the cabinet. Figure 2 is a cross-sectional view taken through the same on the line 2-2 of Figure 1. Figure 3 is a top plan view of the cabinet after it has been opened. 25 Figure 4 is a longitudinal sectional view taken through one of the pockets and the slide connected thereto. Figure 5 is a cross-sectional view taken through the same, showing how the pocket and slide are connected 30 by a projecting tongue on the latter. And Figure 6 is a plan view of one of the budget cards.

Throughout the specification and drawings, similar reference characters denote 35 corresponding parts.

In the accompanying drawings illustrating 40 my invention, the numeral 1 designates a filing cabinet preferably constructed of hard leather, and having a top part 2 to which there is suitably secured an index 45 plate 3. The latter is divided into a front name portion 4 and a rear index portion 5 in front of a transverse slot 6. (See Figures 1 and 3.)

Provided on the index portion 5 of the 50 plate 3 is a series of headings such as "Food", "Clothing", "Rent," etc., disposed lengthwise of the cabinet. While I have employed headings suitable for a home budget system, any other desired ones may be used if desired.

Opposite each heading is a line 7 into registry with which the pointed end 8 of a segmental indicator member 9 is adapted to be

moved. Formed in the indicator member 9 is a slot 10 through which there freely projects a kicker arm 11 that terminates above said member in a finger grip portion 12. Projecting downwardly from the member 9 through the slot 6, and an alined slot below it in the top 2 of the cabinet, is a slotted lug portion 13 that terminates at its lower end in a flange 14 which is adapted to move along the under side of the plate 3. The upper end of the kicker arm 11 is hingedly secured within this lug portion by a pivot piece 15, the lower end of the arm terminating in a rounded portion 16 for engagement with the rear end of each one of a series of slides 17 to be hereinafter more fully described. (See Figures 1, 2 and 3.)

Provided on the rear part of the flange 14 is a projection 18 to which one end of a coil spring 19 is secured, the other end of said spring being attached to an apertured lug 20 on the kicker arm below the member 9. The purpose of this spring is to return the kicker arm to a vertical position after its rounded end is forced inwardly against one of the slides 17.

Formed in the top 2 of the cabinet below the lines 7 that run to the headings on the index plate 3, are slots 21 through which the upper ends of the slides 17 are movable. The lower ends of these slides are longitudinally movable through similar slots 22 provided directly below the slots 21, in the bottom 23 of the cabinet, said bottom being covered underneath by a strip of felt 24 or other soft material. (See Figures 1 and 2.)

To the end of each slide 17, which is bent upon itself to secure stiffness, there is connected in the following manner one side of a card-receiving pocket or folder 25. Referring to Figures 4 and 5, the slide is cut 95 away near its bent-over end to provide a tongue 26 that is forced through the side of the folder, which is preferably made of cardboard, and then turned against its inner surface as shown in Figure 5. This fastening operation is preferably accomplished by a machine made for the purpose; and although I prefer to connect the folder and slide together in this manner, any other means for effecting this result may be employed if desired.

The pockets 25 are maintained side by side within the cabinet by their slides 17 that

project into the slots 21 and 22, each pocket corresponding to one of the headings on the index plate 3 and adapted to contain a number of cards 27 to receive data relating to 5 that heading. (See Figures 1, 2 and 6.)

When it is desired to remove a card from a pocket corresponding to a particular heading, the segmental indicator member 9 is moved into registry with the line 7 leading 10 to that heading. Either before or after this is done, the front end 28 of the cabinet, which is hingedly secured between the side walls of the latter, is opened. The finger grip portion 12 of the kicker arm 11 is then 15 drawn backwardly, whereupon the rounded portion 16 of its lower end will engage and push outwardly the pocket 25 corresponding to the heading opposite which the pointed end 8 of the member 9 stands. When the 20 pocket has been moved a sufficient distance outwardly to disclose to view the front ends of its cards, its further outward movement will be resisted by the engagement of the slide 17 to which the pocket is secured, 25 with the ends of the slots 21 and 22 in the top and bottom respectively of the cabinet. The front ends of the pocket are notched so that the cards which it contains, may be easily grasped by the fingers for removal 30 from it.

After the pocket has been moved to its outermost position, the spring 19 will draw the kicker arm 11 back to its normal position so that the pocket may be pushed inwardly after the cards are reinserted in it. The inward movement of the slides 17 will be limited by their engagement with a cross member 30 secured within the cabinet a little above, and behind, the slots 22. The 40 slots 21 and 22 not only form a guide for the slides 17, but they also serve to limit their outward movement, the inward movement of them being limited by the cross member 30.

45 It will thus be seen that I have provided a filing cabinet in which an indicating member may be easily moved over an index plate to a name or subject thereon, after which, by pulling upon the outer end of a kicker arm, a pocket will be thrust forward by it to present for removal, one or more cards relating to the name or subject selected by the indicating member.

Having described my invention, I claim:

55 1. In a filing cabinet having a top and a bottom which contain at their rear ends vertically aligned slots that run lengthwise of the cabinet, vertical slides movable longitudinally of said slots, a series of card-receiving pockets attached to said slides and adapted to be moved outwardly by them, an index on the top of the cabinet containing a number of headings arranged lengthwise thereon, the top of the cabinet containing a transverse slot behind said headings, an

indicating member movable over the top of the cabinet into registry with said headings, and a kicker arm pivotally secured to said indicating member and terminating at its top end in a finger-gripping portion, and projecting downwardly through the slot in the cabinet top to engage a slide to force outwardly a pocket corresponding to the heading with which the indicating member is aligned, when the top end of said kicker arm is drawn rearwardly. 75

2. In a filing cabinet having a top and a bottom which contain at their rear ends vertically aligned slots that run lengthwise of the cabinet, vertical slides movable longitudinally of said slots, a series of card-receiving pockets attached to said slides and adapted to be moved outwardly by them, an index on the top of the cabinet containing a number of headings arranged lengthwise thereon, the top of the cabinet containing a transverse slot behind said headings, a slotted indicating member movable over the top of the cabinet into registry with said headings, a kicker arm pivotally secured within the slotted portion of said indicating member and terminating at its top end in a finger-gripping portion, and projecting downwardly through said slot in the cabinet top to engage a slide to force outwardly a card-receiving pocket, and a coil spring connected between said indicating member and the kicker arm for the purpose specified. 85

3. In a filing cabinet having a top and a bottom which contain at their rear ends vertically aligned slots that run lengthwise of the cabinet, vertical slides movable longitudinally of said slots, a series of card-receiving pockets attached to said slides and adapted to be moved outwardly by them, an index on the top of the cabinet containing a number of headings arranged lengthwise thereon, the top of the cabinet containing a transverse slot behind said headings, a slotted indicating member movable over the top of the cabinet into registry with said headings, a flanged lug projecting downwardly from said member through the slot in the cabinet top, a kicker arm pivotally secured to said flanged lug and projecting upwardly through the indicating member, and downwardly to engage a slide to force outwardly a card-receiving pocket, a projection on said lug below the top of the cabinet, a projection on said kicker arm below said lug, and a coil spring connected between said projections for the purpose specified. 105

4. The combination with a filing cabinet, of a series of card holders adapted to be moved outwardly therefrom to advanced positions, an index on the top of the cabinet containing a number of headings, an indicating member movable over the top of the cabinet into registry with said headings, the

top of said cabinet containing an opening behind said headings, and a kicker member pivotally secured to said indicating member and projecting downwardly through said opening in the cabinet top to engage and force outwardly a holder containing a card corresponding to the heading with which the indicating member is alined, when the

top end of said kicker member is drawn rearwardly.

In testimony whereof I have hereunto set my hand this 9th day of April, 1923.

MAX C. WHITMORE.

Witness:

HOWARD S. SMITH.
